ICE-CREAM CONE OR THE LIKE

Attilio Agostino Guido Marcantonio, Streatham, London, England, assignor to Embisco Limited, London, England, a British company

Application March 26, 1959, Serial No. 55,184

Claims priority, application Great Britain
November 5, 1958

Term of patent 14 years

(Cl. D8—1)

Fig. 1

Fig. 2

Fig. 3

Fig. 4

I claim:

The ornamental design for an ice-cream cone or the like, as shown.
